UNITED STATES PATENT OFFICE.

DANIEL M. LEE, OF GEORGETOWN, SOUTH CAROLINA.

DOOR-OPERATING MEANS.

Application filed March 26, 1924. Serial No. 702,090.

To all whom it may concern:

Be it known that I, DANIEL M. LEE, a citizen of the United States, residing at Georgetown, in the county of Georgetown and State of South Carolina, have invented certain new and useful Improvements in Door-Operating Means, of which the following is a specification.

My invention relates to mechanically operated doors or closure elements, for use in connection with garages, or the like.

An important object of the invention is to provide means whereby the door may be automatically opened when an automobile or other vehicle is driven into the garage, and then closed, and also opened and closed when the automobile is driven out of the garage.

A further object of the invention is to provide means to lock the door closed when the garage is empty.

A further object of the invention is to provide means to prevent the doors from being opened, from the exterior, when the automobile is within the garage.

A further object of the invention is to provide apparatus of the above mentioned character, which is simple in construction, strong, durable and reliable in operation.

Other objects and advantages of the invention will be apparent during the course of the following description.

In the accompanying drawings forming a part of this specification and in which like numerals are employed to designate like parts throughout the same,

Figure 1 is a side elevation of a door apparatus embodying my invention,

Figure 2 is a horizontal section taken on line 2-2 of Figure 1,

Figure 3 is a longitudinal vertical section taken on line 3-3 of Figure 1,

Figure 4 is a detail vertical section taken on line 4-4 of Figure 2,

Figure 5 is a detail section taken on line 5-5 of Figure 4, and,

Figure 6 is a perspective view of a lock device.

In the drawings, wherein for the purpose of illustration is shown a preferred embodiment of my invention, the numeral 10 designates a garage or other building, as a whole, having its front end open, and adapted to be closed by doors 11. The garage is equipped at the rear end with the usual side door, whereby access may be had thereto,

as is well known. While I prefer to employ two doors 11, the invention is not restricted to this practice, as satisfactory results could be obtained by the use of one large door. 60 In the claims, the term "door means" is intended to cover either one or two doors.

The doors 11 are connected with the front end of the garage by means of hinges 12, to swing horizontally, and these hinges are 65 preferably of the ball bearing type. Rigidly attached to the outer side of the left door 11, Figure 1, at its top, is a bracket 13, carrying a vertical shaft 13', in alinement with the hinges 12. This shaft has a beveled gear 70 14, rigidly mounted thereon, engaging a beveled gear 15. This beveled gear is rigidly mounted upon a horizontal shaft 16, journaled in bearings 17. These bearings are attached to the top portion of the garage 75 above the doors. A beveled gear 18 is rigidly attached to the opposite end of the shaft 16 and engages a beveled gear 19, rigidly mounted upon a shaft 20. This shaft 20 is in alinement with the adjacent hinges 12 80 and is rigidly attached to a bracket 21, which is rigidly attached to the right door 11, Figure 1, at the top thereof. Brackets 22 are rigidly attached to the doors 11, near their lower ends, and carry depending shafts 85 23. The shaft 23 to the left is journaled in a vertical stationary bearing 24, while the shaft 23 to the right is journaled in a bracket 25, fixed to the garage.

As more clearly shown in Figure 5, a 90 beveled gear 26 is rigidly mounted upon the shaft 23, to the left, and engages a beveled gear 27, rigidly mounted upon a transverse horizontal drive shaft 28, journaled within openings formed in plates 29 of a housing 30, which may be suitably located within the garage. The drive shaft 28 has a gear 31 rigidly mounted thereon, within the housing, and this gear engages a rack bar 32, reciprocating within the housing, and projecting 95 through an opening 33 in the front wall of the garage. This rack bar is equipped with gear teeth 34. The rack bar 32 is moved rearwardly or inwardly by a retractile coil spring 35, of suitable stiffness, having connection at its forward end with a bracket 36, rigidly attached to the rack bar 32. The rear end of this spring is attached to a stationary horizontal arm 37, which is rigidly attached to the housing, as shown. 100

The numeral 38 designates a trip or de-pression element as a whole, which is ar-

ranged at the forward end of the garage, and projecting into the garage and outwardly beyond the same. This trip element embodies an intermediate preferably rigid 5 wheel engaging section 39, and inclined outer sections 40, hinged thereto at 41. The intermediate section has pivotal connection, at 42, with horizontal arms 43, carried by vertically swinging cranks 44, arranged there- 10 beneath. These cranks 44 are rigidly connected with rock shafts 45, journaled in brackets 46. The rock shafts 45 are pro- 15 vided with upstanding cranks 47, having pivotal connection with links 48 and 49, which are preferably rigid, and having their inner ends pivotally connected with the op- 20 posite ends of the rack bar 32. It is thus seen that when an automobile is passing through the opening of the garage, it will 25 depress the intermediate section 39 on the trip element, and this depression causes the trip element to move longitudinally out- 30 wardly. This occurs when the automobile is moved into the garage or is being driven 35 out of the same, the trip element moving out- 40 wardly in both instances. When the trip element 38 moves outwardly, the rack bar 32 moves outwardly and this movement rotates the gear 31 and its shaft 28. This rotates 45 the beveled gear 27 which rotates the beveled gear 26. The beveled gear 26 being rigidly attached to the door 11 to the left causes it to swing outwardly, and the door 11 to the 50 right swings outwardly, as it is geared thereto. When the pressure is moved from the trip element, the spring 35 brings the rack bar 32 rearwardly, and the doors are 55 closed.

The doors are not equipped with the usual 40 lock or latch, and it is desirable that they be held against undue rattling or restricted movements, which might be caused by the wind or the like. For this purpose, I pro- 45 vide means for locking the rack bar 32 against outward longitudinal movement, when the doors are closed, and the trip ele- 50 ment 38 is elevated. This means embodies a reciprocating bolt 49', operating through a stationary guide 50, and movable into en- 55 gagement with the teeth 34. This bolt has pivotal connection at its lower end with a crank 51, carried by a rock shaft 52, jour- 60 naled within bearings 53. The rock shaft carries at its opposite end a crank 54, pro- 65 vided with a horizontal arm 55, engaging above the intermediate section 39. When this intermediate section rises, it turns the rock shaft 52 and the bolt 49' engages the teeth 34. This bolt may be released from 70 the exterior of the garage, by the manual depression of the trip element.

It is desired to provide means to render it impossible to open the doors from the exterior thereof, when the garage is occupied 75 by an automobile, and to accomplish this I

provide a car engaging element 56, prefer- 80 ably arranged to engage behind the wheel of the automobile, although it may engage some other part of the automobile. This car 85 engaging element embodies a rock shaft 57, journaled in a bracket 58. This rock shaft carries an upstanding crank 59 having a horizontal arm 60, to engage behind the wheel of the automobile. The rock shaft 57 carries an upstanding crank 61, pivotally 90 connected with a link 62, in turn pivotally connected with the rear crank 47.

For the purpose of illustration, I have shown the opening beneath the doors 11 closed by a beam or sill 63, which may pref- 95 erably be formed of concrete and this sill has openings 64 for receiving the wheels of the automobile, the trip element 38 being ar- 100 ranged in one of these openings. It is to be understood that the invention is in no sense restricted to this particular use of sill ar- 105 rangement, as the same may be dispensed with, if desired.

The operation of the apparatus is as fol- 110 lows:

With the doors 11 closed, when the auto- 115 mobile approaches these doors, it passes upon the outer end of the trip element and de- 120 presses it. When this occurs, the bolt 49 drops by gravity, from engagement with the rack bar teeth 34, and of course the arm 55 could be mechanically connected with the trip element, if desired. The rack bar 32 now moves forwardly and the doors are 125 opened. The automobile passes into the ga- 130 rage and when it is driven off of the rear end of the trip element the spring 35 moves the rack bar 32 inwardly and the doors are 135 closed. When the automobile is moved to the inner end of the garage, its wheel en- 140 gages in front of the arm 60, and the rock shaft 57 is locked against turning movement. The trip element cannot now be depressed from the exterior of the garage, since the 145 rack bar 32 cannot move forwardly. When 150 it is desired to drive the automobile out of the garage the forward movement of the same depresses the trip element 38 and the doors are opened, which again close when 155 the automobile passes from these trip ele- 160 ments.

It is to be understood that the form of my invention herewith shown and described is to be taken as a preferred embodiment of 165 the same, and that various changes in the 170 shape, size, and arrangement of parts may be resorted to, without departing from the 175 spirit of my invention, or the scope of the 180 subjoined claims.

Having thus described my invention, I 185 claim:

1. In door operating means, door means, 190 means including a rack bar to open the door means, a spring to close the door means, a trip element to move the rack bar in one di- 195

rection, a latch to engage with the rack bar to hold it against movement, and means operated by the trip means to release the latch.

2. In door operating means, door means, means including a rack bar to open the door means, a spring to close the door means, a trip element to move the rack bar in one direction, a latch to engage with the rack bar to hold it against movement, means operated by the trip means to release the latch, and a car engaging latch device connected with the rack bar to hold it against movement when engaging with a part of a vehicle.
3. In door operating means, door means, means including a substantially horizontal rack bar to open the door means, said rack bar projecting upon the inner side of the door means, a trip element connected with the rack bar to move the same when the trip element is depressed, a stationary substantially horizontal arm arranged upon the inner side of the door means near the substantially horizontal rack bar, a retractile coil

spring connected with the rack bar and stationary arm to move the rack bar in one direction, and latch means to hold the door means in the closed position, said latch means including a part engaging the trip element.

4. In door opening means, door means, means including a rack bar to open the door means, a trip element to move the rack bar in one direction, and a vehicle engaging lock device connected with the rack bar to prevent its movement when such device is engaging a part of the vehicle.

5. In door operating means, door means, a trip element having a part to be depressed, operative connection between the trip element and door means whereby the door means is moved by the trip element, means to normally lock the door means in the closed position, and means whereby the locking means releases the door means upon the depression of the trip element.

In testimony whereof I affix my signature.
DANIEL M. LEE.
